UNITED STATES PATENT OFFICE.

WILLIAM KENNISH, OF BROOKLYN, NEW YORK, ASSIGNOR TO ANDREW B. GRAY, OF SAN DIEGO, CALIFORNIA.

SUBMARINE EXCAVATOR.

Specification of Letters Patent No. 17,306, dated May 12, 1857.

To all whom it may concern:

Be it known that I, WILLIAM KENNISH, of Brooklyn, in the county of Kings and State of New York, have invented a new and useful machine, called "Kennish's Submarine Hydrostatic Excavator," for the purpose of removing bars or deposits of mud or sand or other movable obstructions from the mouths or bottoms of harbors and rivers, docks, or other places covered with water; and I do hereby declare that the following is a full, clear, and exact description of the construction and operation of the same, reference being had to the annexed drawings, making part of this specification, in which—

"Plate 1" is a perspective view and "Plate 2" is a section of the apparatus in operation.

20 In Plate 1 A is the excavator which I construct of sheet iron or any other substance having the requisite power of resistance. Its shape is a frustum of a cone or a cylinder with bows and stern attached in order 25 that it may be the more easily towed through the water or held fast in tideways.

B is the converging pipe which sinks into the bed of the river, harbor, &c., and through which the mud, sand, stones or other substances pass into the excavator.

30 In Figure 1 "Plate 2" 8, 8, is the outer chamber of the excavator into which air is injected for the purpose of raising the machine when full, and from which the air is withdrawn, water taking its place, for the purpose of sinking the machine to the bottom preparatory to forming a vacuum in the inner chamber.

35 C, C, are the discharge valves the opening of which allows the mud, &c., to fall from the chamber. These valves are kept shut by the balancing weights 7, 7, which weights are sufficiently heavy to keep the valves closed when the inner chamber is full of the 40 material to be lifted.

45 The chains f, f, joining at h, are for the purpose of lifting up the weights 7, 7, when the mud, &c., in the inner chamber will press down the valves C, C, and find its escape through them.

50 L, L, are the water tight tubes set into the outer chamber of the excavator in which the weights 7, 7, rise and fall.

X, X, are the water-tight tubes through

which the chains pass connecting valves C, C, 55 with the balancing weights.

D is the pipe to which the hose H, is attached for the purpose of forcing air into, or withdrawing it from the inner chamber.

E is the pipe to which the hose K is attached for the purpose of forcing air into the outer chamber when the machine is to be lifted and of allowing the air to escape when it is to sink.

In Plate 1 N, is a cylindrical compartment 65 made for the purpose of forming a vacuum in order to extract the air from the inner chamber of the excavator. The connection between this chamber and the cylinder is through pipe g, pass cocks P and R and 70 hose H.

M Plate 1 is a cylinder of the same capacity and similarly constructed to the cylinder N for the purpose of forcing air into the outer chamber of the excavator. The 75 connection between the cylinder M and the outer chamber of the excavator "8, 8" Fig. 2, Plate 2, is through the pipe "g," pass cocks "G" and "S" and hose "K."

"m" is a pipe leading to the boiler and 80 transmits steam into the cylinders M and N.

I will now describe its operation.

The receiver "A" Plate 1, as shown in the accompanying diagrams is on the bottom of the river or harbor, and the mud, stones, &c., 85 are rushing up pipe B, into chamber 9 Plate 2. The air which was previously there having nearly all passed up through hose H, pass cocks R and P into the vacuous space in N. The chains and hose are all loose to 90 allow the excavator to sink or rise without restraint. When the inner chamber is charged with the material to be lifted, the cock R, is turned off and the cocks G and S are opened, a communication is thus formed 95 between the outer chamber of the excavator and the cylinder M. The cock "a" is then turned on admitting steam into cylinder M and forcing the included air by its sudden rarefaction and force into the outer chamber 100 of the excavator until all the water previously there is expelled through the holes Z, Z, when the receiver rises gradually until it floats permanently on the surface. While it is rising the rollers are turned around, 105 tightening up the chains 9, so as to secure its position when it reaches the top; the excavator is then towed into deep water or

whatever place the material lifted is to be deposited and having arrived there the valves "C, C," are relieved of the weights 7, 7, by the rope "b" which connects with 5 the chains "f, f," and passes over a pulley on the deck of the ship. The valves having been thus relieved, will fall open, allowing the mud to fall out, water taking its place; the weights "7, 7," are again let fall, which 10 closes the valves "C, C," and the receiver is towed back to its original position.

The weight or quantity of the material lifted may be ascertained by a gage attached to the outside of the excavator marking its 15 line of flotation. When the inner chamber 9 is full, the excavator will be about a foot out of water, and when it is not full, the gage will indicate accordingly.

When the excavator is towed back to its 20 original position, the cocks "S, P," and T, are turned, allowing the air in the outer chamber of the excavator to pass out through hose "K" into the pipe "g" and pass cocks T and P into cylinder N and thence into 25 the outer atmosphere through valve 4. By this means the excavator gradually sinks until it reaches the bottom. In this state the outer chamber of the excavator is quite filled with water which enters through the 30 holes Z, Z, upon the withdrawal of the air, and the inner chamber is nearly filled with water, as the air, which before its descent nearly half filled it, is compressed to half its volume. Before forming the vacuum in 35 the reservoir N it is necessary to expel this water, which is done by opening cocks G, T and R, and forcing the air by the injection of steam as before described. The air by this means, being forced into the inner 40 chamber the water is expelled through valves C, C, which are relieved of weights 7, 7, for that purpose. When air is seen bubbling to the surface, it is a sure indication that the inner chamber is entirely filled with air

and the weights are then let down which closes the valves. The excavator is now ready for a second charge, a vacuum having been already formed in the cylinder N by 45 the injection of steam through steam cock e and its subsequent condensation by a jet of water being thrown upon it through condensing pipe J. The cocks "P" and "R" are then turned on, when the air, from inner chamber 9 of the excavator, will rush into the vacuum thus formed, creating in chamber 9, a vacuum into which the mud, sand or stones, at the bottom of the river or harbor will rush at the same time, the hydrostatic pressure at the top of the excavator will force it down into the mud, thus 50 constantly keeping the mouth of the pipe "B" below the surface of the mud and gaining twice the hydrostatic pressure by the excavator being wholly independent of any boat or other body having a fixed position except 55 by pliable chains and hose.

I do not claim as new forming a vacuum by steam as this has been done before, nor do I claim to be the first to use such vacuum for the purpose of excavation; but 60

What I claim as my invention and desire to secure by Letters Patent is—

1. I claim the combination and arrangement of the chambers 8 and 9, with the pipe, B, valves C, C, and weights 7, 7, or of any 75 equivalents thereof; for the purposes herefore specified.

2. I also claim the arrangements of the cylinders N and M, with their pipes and 80 hose, or the equivalents thereof, whereby the mud chamber 9, and floating chamber 8, are alternately filled with, or emptied of air, as the means of collecting and floating off the excavated material.

WM. KENNISH.
